UNITED STATES PATENT OFFICE.

GEORGE E. THORNBURG, OF WINCHESTER, INDIANA.

ENVELOP.

1,071,189.

Specification of Letters Patent. Patented Aug. 26, 1913.

Application filed May 12, 1913. Serial No. 767,185.

To all whom it may concern:

Be it known that I, GEORGE E. THORNBURG, a citizen of the United States, residing at Winchester, in the county of Randolph 5 and State of Indiana, have invented a new and useful Envelop, of which the following is a specification.

The object of my invention is to provide an envelop of novel construction in which 10 all flaps interlock to securely fasten the envelop without the use of adhesive, and which also affords means for inspecting the contents without unfastening all flaps of the envelop.

15 It is also an object of my invention to provide an envelop of novel construction that when sealed with adhesive can not be opened or broken into without tearing.

It is also an object of my invention to provide an envelop or packet-closure of the 20 novel construction set forth suitable for wrapping all classes of mail, etc.

My invention is set forth in the accompanying drawings in which—

25 Figure 1 is a plan view of the back of the envelop, folded except for the top flap; Fig. 2 is a plan view showing the end flaps folded and interlocked but with the top and bottom flaps open; Fig. 3 is an enlarged cross sectional view through the center of the envelop; Fig. 4 is a plan view of the envelop-blank, before folding.

30 As illustrated in Fig. 4, which shows the envelop-blank, I provide a body or front portion 1; a top flap 2, having a tongue 3; a bottom flap 4 having a segmental slot 5; and end flaps 6 and 8. End flaps 6 and 8 have concave longitudinal edges so that when folded together over the inclosure, the 35 nature of the contents may be noted without unfastening the end flaps. End flap 6 is provided with a substantially vertical slit 7, as a locking means. End flap 8 is provided with a tongue 9 vertically extending lip 40 10. An angular slot is formed in end flap 8 by edges 11 and 12, the latter corresponding substantially with slot 5 and tongue 3.

45 In operation end flap 8 is folded over end flap 6; tongue 9 is inserted through slit 7; 50 and the two flaps are retained in locked relation by lip 10, as shown in Fig. 2. Bottom flap 4 is then folded over end flaps 6 and 8,

as shown in Fig. 1, in which position the base line of segmental slot 5 substantially coincides with edge 12 of flap 8. Top flap 2 55 is then folded over bottom flap 4 and tongue 3 is inserted through segmental slot 5 and also inserted through the angular slot formed by edges 11 and 12 of flap 8. Bottom flap 4 is thus held in a locked relation 60 by means of tongue 3, with end flap 8, which in turn is locked to flap 6. The relative position of the tongue and flaps and manner in which it is inserted to securely lock the envelop is illustrated in Fig. 3. A securely 65 fastened envelop is thus provided adapted for inclosing various classes of unsealed mail matter, etc.

It is also within the contemplation of my invention to add the usual adhesive or sealing gum along the inner edges of bottom flap 4 and top flap 2 and tongue 3, to provide a safety envelop for first class mail, to provide an envelop for first class mail which can not be opened without tearing, as tongue 70 3 would be inserted through segmental slot 5 and beneath edge 12 of flap 8 and sealed to end flap 6, which is the innermost flap. The segmental shape of slot 5 would permit of the insertion of the gummed tongue 75 80 easily without scraping off the adhesive.

What I claim is:

An envelop comprising a front portion; end flaps foldable toward each other, one of the flaps being provided with a substantially 85 vertical slit extending from the edge of the flap approximately to its center and the opposite flap being provided with an end tongue insertible through the aforesaid slit in the opposite flap, and having a vertically 90 extending lip formed on the tongue to secure the two end flaps in locked relation, and also having an angular slot opposite the aforesaid lip; and a bottom flap foldable over the 95 end flaps and having a slot substantially coinciding with the angular slot; and a top flap foldable over the bottom flap and having a tongue insertible through the slotted bottom flap and slotted end flap, whereby all flaps are securely interlocked.

GEORGE E. THORNBURG.
